LOUIS H. VON OHLSEN, OF NEW HAVEN, CONNECTICUT, ASSIGNEE TO THE SAFETY CAR HEATING & LIGHTING COMPANY, A CORPORATION OF NEW JERSEY

SYSTEM AND APPARATUS FOR ELECTRIC REGULATION

Application filed March 30, 1930. Serial No. 437,439.

This invention relates to a system and apparatus for electric regulation.

One of the objects of this invention is to provide a simple and thoroughly practical system and apparatus for achieving regulation in an electrical circuit or system that will be well adapted to meet the varying conditions of practical use. Another object is to provide a regulating system and apparatus of the carbon pile type in which a wide range of action may be achieved in spite of the relatively limited range of action inherent in the carbon pile itself. Another object is to provide a system and apparatus of the carbon pile type in which the range of action may be diminished or increased without necessitating the removal from or addition to the carbon pile of individual carbon resistance elements. Another object is to provide a system and apparatus of the above-mentioned character that will be foolproof, thoroughly dependable in action, free from undue mechanical or electrical complications, and capable of effecting regulation throughout a wide range of practical conditions. Another object is to provide a system and apparatus of the above-mentioned character that will be capable of embodiment in inexpensive form and that will be of simple operation. Other objects will be in part obvious or in part pointed out hereinafter.

The invention accordingly consists in the features of construction, combinations of elements, and arrangements of parts as will be exemplified in the structure to be herein-after described and the scope of the application of which will be indicated in the following claims.

In the accompanying drawings in which are shown several possible embodiments of my invention,

Figure 1 is a diagrammatic representation of the regulating system and apparatus, and

Figure 2 is a modified form thereof.

Similar reference characters refer to similar parts throughout the several views in the drawings.

As conducive to a clearer understanding

of certain features of my invention, it might at this point be noted that the effective range of action of a carbon pile regulator is insufficient to meet certain practical requirements or conditions of use, particularly, for example, in systems where it is necessary to operate at different times at different voltages throughout a substantial range of voltages. In such instances the range or capacity of action of the carbon pile itself is insufficient and it has heretofore been necessary to resort to such cumbersome and troublesome expedients as removing from or adding to the carbon pile an appropriate number of carbons to effect a change in the action or range of the carbon pile. One of the dominant aims of this invention is to provide a system and apparatus that avoid such difficulties as these and that will make it possible readily and conveniently to suit the carbon pile regulator to the conditions to be met.

Referring now to the drawings and more particularly to Figure 1, I have shown diagrammatically a carbon pile regulator which includes a carbon pile 10 controlled by a coil 11 acting thereon through a bell crank lever 12 pivoted at 13, the coil 11 acting in opposition to a spring 14 which tends to compress the carbon pile 10. The carbon pile regulator is to regulate or control a function of the output of a source of current and by way of illustration I have shown the latter as taking the form of a generator 15 supplying current to any suitable load through the mains 16 and 17, the generator 15 being illustratively of the shunt field type and having a shunt exciting field 18.

The carbon pile 10 is connected in series with the shunt field 18 but through a rheostat or variable resistance 19—20, the resistance element 19 of which being provided with a suitable number of contacts with which the contact arm 20, rotatable about an axis 21, coacts in order to vary the amount of resistance in series with the carbon pile 10 and the field 18.

More specifically, the shunt field circuit will be seen to extend from one side of the generator 15, thence through the field 18, 100

through the carbon pile 10, and by way of conductor 22 to the switch arm 23 of a reversing switch, one contact 24 of which is connected by conductor 25 to one end of the resistance 19 and the other contact 26 of which is connected by conductor 27 to the other end of the resistance 19 of the rheostat; the circuit is completed by way of rheostat arm 20 and thence by conductor 28 to the other side of the generator 15.

The coil 11 which controls the pressure on the carbon pile 10 is illustratively shown as a voltage responsive coil, being connected to be responsive to the voltage of the output 15 of the generator 15.

More specifically, the circuit of coil 11 will be seen to extend from one side of the generator 15, such as the main line 17, thence by way of conductor 29 through the coil 11, conductor 30 to one end of the resistance 31 of a rheostat 31-32, then by way of rheostat arm 32 and conductor 33 back to the other side (main 16) of the generator 15.

The resistance 31 is sub-divided into a suitable number of steps, much in the same way as is the resistance 19 of the rheostat 19-20, and these steps are provided with a suitable number of contacts with which the rheostat arm 32, which is pivoted at 34, may coact as the rheostat arm is rotated.

The rheostat arm 32 is provided with an insulated handle 35 to permit manual operation thereof while rheostat arm 20 of the rheostat 19-20 is likewise provided with an insulated handle 36, the two handles being connected together to move in unison by means of an adjustable link 37, adjustable as to length by means, for example, of a turn buckle 38.

Preferably the carbon pile regulator and the two rheostats and also the reversing switch 23 are mounted upon a single panel diagrammatically indicated at 39.

Assuming the reversing switch 23 to be in the position shown in Figure 1, it will be noted that the rheostat 19-20 is connected in circuit with the carbon pile 10 so that movement of the rheostat arm 20 in counter-clockwise direction decreases the resistance in series with the carbon pile 10. The rheostat arms 20 and 32, however, are mechanically connected, as above described, so that a change in the resistance of rheostat 19-20 is accompanied by a change in the resistance placed in the circuit of the regulating coil 11 by the rheostat 31-32, and with the reversing switch 23 positioned as above noted, any setting of the rheostat 35 in counter-clockwise direction is accompanied by a similar setting or movement of the rheostat arm 20 in counter-clockwise direction. Rheostat 31-32 thus increases the resistance in circuit with coil 11 and changes its standard of operation in such a way that it will now require a higher voltage to effect a change

in the pressure on the carbon pile 10 against the action of spring 14. At the same time, the resistance represented by the rheostat 19-20 in series with the carbon pile 10 has been diminished, changing per se the standard of operation of the carbon pile 10 and, in effect, shifting its range of action.

Should the operating characteristics of the load require a lower voltage, a reverse adjustment of the rheostat 31-32 is accompanied by a reversed change in the rheostat 19-20; the regulating coil 11 is thus set to respond to a lower voltage and the range of action of the carbon pile 10 is shifted in the direction of a lower standard of field current 80 to meet the lower standard of voltage regulation now achieved by the regulating coil 11.

The turn buckle 38 may be utilized preferably to suit or inter-relate the two rheostats to achieve the desired inter-relation between the changes in standard of operation which the two rheostats effect.

On the other hand, the characteristics of the load supplied by the generator 15 may 90 be or become such as to require a different inter-relation between the changes in standards of operation effected by the rheostats. The reversing switch 23 is then moved toward the right, as viewed in Figure 1, and 95 reverses the relation of the rheostat 19-20 with respect to the operation of the rheostat 31-32. A counter-clockwise movement of the rheostat arm 32, while still accompanied by a counter-clockwise movement of the rheostat arm 20, achieves an increase in the resistance in circuit with the carbon pile 10, instead of a decrease, as was the case where the reversing switch 23 was in contact with the contact 24. While, therefore, an increase in the standard of voltage regulation is achieved by such counter-clockwise setting of the rheostat arm 32, the range of action of the carbon pile 10 is shifted to a lower standard of field current. 100 A setting of the rheostats in reverse direction achieves, as will now be clear in view of the foregoing, reversed changes in the respective standards of operation of the controlling coil 11 and the carbon pile 10.

Thus I am enabled to meet a wide range of change in the requirements imposed upon the regulating apparatus either by the generator itself and the characteristics of the latter, or by the character of the load supplied by the generator. More particularly, it will be seen that the regulating apparatus makes available the full range of variation or action of the carbon pile 10 even though practical requirements of the circuit system or apparatus to be regulated necessitate changes in the constants of the related circuits greater than that of which the carbon pile 10 itself is capable of effecting.

Moreover, the regulating apparatus will 130

be seen to have such a wide range of action and such flexibility of manual control that it can be very readily and quickly suited to the characteristics of any particular generator or circuit or apparatus to be regulated, and that I am enabled to avoid the necessity of designing or building a special regulator for each different condition met with in practice.

Turning now to Figure 2 of the drawings, I have shown a possible modification of the arrangement of Figure 1, and more particularly it will be noted that the resistance 19 of the rheostat 19—20 is shunted about the carbon pile 10 by conductors 40 and 41 through a reversing switch generally indicated at 42. The functioning and operation of the arrangement of Figure 2 is substantially identical to those of the system of Figure 1, excepting that the range of action or standard of operation of the carbon pile 10 is affected by changing the amount of resistance of the rheostat 19—20 in parallel with the carbon pile 10 instead of effecting such a change by changing the resistance in series with the carbon pile 10, as is the case in Figure 1. The arrangement of Figure 2 is particularly adaptable to conditions where the regulating circuit in which the carbon pile 10 is included carries a current materially in excess of the maximum current which the carbon pile 10 itself is intended to carry. The operation and functioning of the system and apparatus of Figure 2 will be clear, it is believed, in view of the detailed description hereinbefore set forth in connection with Figure 1.

As many possible embodiments may be made of the above invention and as many changes might be made in the embodiment above set forth, it is to be understood that all matter hereinbefore set forth, or shown in the accompanying drawings, is to be interpreted as illustrative and not in a limiting sense.

I claim:

1. In an electrical system, in combination, a source of current, a carbon pile for regulating a function of the output of said source, a coil responsive to a function of the output of said source for controlling said carbon pile, a variable resistance in series with said carbon pile for changing the range of action of said pile, a variable resistance in series with said coil for changing the standard of operation thereof, means for conjointly varying said variable resistances, and means connecting one of said resistances in its circuit whereby its action in its circuit may be reversed.

2. In an electrical system, in combination, a source of current, a carbon pile for regulating a function of the output of said source, a coil responsive to a function of the output of said source for controlling

said carbon pile, a variable resistance in series with said carbon pile for changing the range of action of said pile, a variable resistance in series with said coil for changing the standard of operation thereof, and operating means for said variable resistances adapted to decrease one resistance as the other resistance is increased.

3. In an electrical system, in combination, a source of current, a carbon pile for regulating a function of the output of said source, a coil responsive to a function of the output of said source for controlling said carbon pile, a variable resistance related to said carbon pile for changing the range of action of said pile, a variable resistance in series with said coil for changing the standard of operation thereof, operating means for said variable resistances, and means operable at will for causing the effects of said variable resistances to be either differential or cumulative in their action upon the system.

4. In an electrical system, in combination, a source of current, a carbon pile for regulating a function of the output of said source, a coil responsive to a function of the output of said source for controlling said carbon pile, a variable resistance in series with said carbon pile for changing the range of action of said pile, a variable resistance in series with said coil for changing the standard of operation thereof, means for conjointly varying said variable resistances, and a reversing switch for reversing the action of one of said variable resistances.

5. In an electrical system, in combination, a source of current, a carbon pile for controlling a function of the output of said source, said carbon pile having an inherent range of change of resistance that is unsuited for controlling said function, and means for adapting said pile to control said function, said means including a coil responsive to a function of the output of said source for varying the pressure on said carbon pile, means for simultaneously changing the operating range of said carbon pile and changing the standard of operation of said coil, and means operable at will for changing the relation between the range of change of operating range of the carbon pile and the range of change in the standard of operation of said coil.

6. In an electrical system, in combination, a source of current, a carbon pile for controlling a function of the output of said source, said carbon pile having an inherent range of change of resistance that is unsuited for controlling said function, and means for adapting said pile to control said function, said means including a coil responsive to a function of the output of said source for varying the pressure on said car-

- bon pile, a variable resistance for changing the standard of operation of said coil, and adjustable means responsive to the actuation of said variable resistance for affecting the range of action of said carbon pile, whereby the relation between the change of standard of operation of said coil and the change in the range of action of said carbon pile may be varied.
- 10 7. In apparatus of the character described, in combination, a regulator panel including a carbon pile and a coil for controlling the pressure on said carbon pile, said coil being adapted to operate at a certain standard and 15 said carbon pile having a certain inherent range of change of resistance, and means for suiting said coil to function at a different standard and for changing the standard at which said inherent range of change of resistance in said carbon pile takes place, said means including a rheostat connected in circuit with said coil, a rheostat connected in circuit with said carbon pile, and means for reversing the action of one of said rheostats 20 relative to the other.
8. In apparatus of the character described, in combination, a regulator panel including a carbon pile and a coil for controlling the pressure on said carbon pile, a rheostat connected in circuit with said coil, a rheostat connected in circuit with said carbon pile, means for conjointly operating said rheostats, and means operable at will for reversing the action of one of said rheostats relative to the other.
9. In apparatus of the character described, in combination, a regulator panel including a carbon pile and a coil for controlling the pressure on said carbon pile, a rheostat connected in circuit with said coil, a rheostat connected in circuit with said carbon pile, means for conjointly operating said rheostats, and switching means for reversing the connections of one of said rheostats to reverse its action relative to the action of the other rheostat.
10. In apparatus of the character described, in combination, a regulator panel including a carbon pile and a coil for controlling the pressure on said carbon pile, said coil being adapted to operate at a certain standard and said carbon pile having a certain inherent range of change of resistance, and means for suiting said coil to function at a different standard and for changing the standard at which said inherent range of change of resistance in said carbon pile takes place, said means including a rheostat connected in circuit with said coil, a rheostat connected in circuit with said carbon pile, and means of adjustable length connecting the movable parts of said rheostats so that operation of one rheostat effects operation of the other.
11. In an electrical system, in combination, a source of current connected to supply energy to a load, means including a variable resistance for controlling a function of the energy supplied to said load, means including a coil responsive to said function of the energy supplied to said load for varying said variable resistance, means for changing the action of said variable resistance, means for changing the standard of operation of said coil, and means for causing said two last-mentioned means to act differentially or cumulatively in their effects upon the system.
12. In an electrical system, in combination, means forming a source of current requiring, for its regulation, a certain range of change of resistance at a given standard, a carbon pile having a sufficient range of change of resistance but having an inappropriate resistance for regulating said means and connected to regulate said means, a coil adapted inherently to function at a certain standard inappropriate to the standard required by said source and intended to be connected to respond to a function of the output of said means, said coil controlling said carbon pile, and means for changing the standards at which said coil and said carbon pile are to function to meet the requirements of said first-mentioned means, said second-mentioned means including a device for changing the standard at which said range of change of resistance in said carbon pile takes place and a device for changing the standard of operation of said coil and means for operating said devices.
- In testimony whereof, I have signed my name to this specification this 10th day of March, 1930.
- LOUIS H. VON OHLSEN.
